ATTORNEY.

UNITED STATES PATENT OFFICE.

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY.

DRAFT AND BUFFING MECHANISM.

Application filed March 16, 1921. Serial No. 452,832.

To all whom it may concern:

Be it known that I, VICTOR WILLOUGHBY, residing at Ridgewood, in the county of Bergen, and State of New Jersey, and being a citizen of the United States, have invented certain new and useful Improvements in a Draft and Buffing Mechanism, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Figure 1 is a vertical longitudinal section taken on line 1—1 of Fig. 2, showing the yoke and contained parts assembled with the car underframe;

Figure 2 is a plan view of the device;

Figure 3 is a front view of the same;

Figure 4 is a vertical transverse section taken on line 4—4 of Fig. 1 looking in the direction indicated by the arrow;

Figure 5 is a view similar to Fig. 1 but illustrating a modification;

Figure 6 is a plan view thereof; and

Figure 7 is a vertical transverse section taken on line 7—7 of Fig. 5;

My invention relates to draft and buffing mechanism for use in mine and other industrial cars having their understructures made up of longitudinal and transverse framing members.

The principal object of my invention is to provide a mechanism comprising in part certain members of the car framework.

Another object is to provide a draft and buffing mechanism having its supporting part slidably mounted upon and embracing associated car frame members.

In the drawings, 10 and 11 represent respectively the end sill and crosstie members of a car underframe, and 12 indicates the yoke member of the mechanism slidably mounted upon and enclosing the frame members 10 and 11. The yoke 12 comprises top wall portion 13, depending front and rear end or foot portions 14 and 15 having in-

wardly extending flanges 16 and guide pieces 17 extending under the frame members and resting upon and secured to the foot flanges 16. The guide pieces 17 are spaced apart as shown to receive between them an anchor strip 18 secured at its ends to the framing members 10 and 11 for guiding the yoke in its movements and serving to prevent lateral displacement of said yoke during service operations. These functions may be performed with the positions of the yoke 65 guide pieces 17 and anchor strip 18 reversed if desired; the guide pieces 17 may be secured to the framing members and the anchor strip 18 to the yoke 70 foot portions 14 and 15, but the disposition of the parts as shown is preferred. The guide pieces 17 are removably secured to the yoke foot flanges 16 to facilitate assembling and disassembling of the yoke with car framing members.

In front of the end sill 10 and moving with the yoke 12 is a coupling piece 19 having its body portion 20 secured to the buffing foot 14 of the yoke and provided with a protruding head portion 21 formed to receive between it and top wall 13 of the yoke 12 a coupling link 22 or other like device.

The mechanism further comprises a resilient element 23 supported between the framing members 10 and 11 upon follower thimbles 24 moving in openings 25 in webs 26 of the framing members. The follower thimbles 24 ride upon webs 26 which serve as bearings for supporting said thimbles, but owing to lack of sufficient bearing area in such webs 90 to properly guide the thimbles in their movements, such thimbles are cored out to receive an alining rod 27 extending through the foot portions 14 and 15 of the yoke 12 and removably secured by a nut 28, or in any other 95 way.

It may be found desirable to dispense with alining rod 27 by increasing the bearing areas for the follower thimbles 24 as illustrated in Figs. 5, 6 and 7. As shown in Fig. 5, additional bearing brackets 29 have been provided to supplement the relatively slight bearing area afforded by the thickness of the webs 26 of the framing members. The bearing brackets 29 are provided with wings 100 30 perforated to receive attaching means 31 for securing same to the framing members. The bearing area thus provided for each

follower thimble will prevent relative displacement of resilient element 23 and the follower thimbles 24.

It will be noted that the follower thimbles 24 are cylindrical in form and provided adjacent one end thereof with an enlarged portion 32 adapted to limit movement of said thimbles in one direction under the expansive action of the resilient element 23, and 10 serves as a seat for said resilient element which, in the form shown, is arranged to receive protruding portions 33 on the thimbles.

The mechanism as shown is in position to 13 respond to either draft or buffing operations. A buffing operation against the mechanism shown in Fig. 1 will cause yoke 12 to move rearwardly, causing the buffing foot 14 to bear against adjacent follower thimble 24, 20 forcing enlarged portion 32 thereof to recede from the web of the end sill and compress spring 23. During this operation, yoke 12, alining rod 27, and the follower thimble adjacent end sill 10 will have moved 25 against the expansive action of the spring, but the yoke top wall portion 13, guide pieces 17, and alining rod 27 will not have been subjected to compressive stresses. Under reverse movement, a pull on draft piece 19 30 will cause yoke foot portion 15 to approach crosstie 11 and force the enlarged portion 32 of adjacent follower thimble 24 against the spring.

What I claim is:

35 1. The combination with an end sill and adjacent crosstie member of a car under-frame, of a draft and buffing mechanism comprising a yoke member having depending foot portions embracing said framing members, guide means extending under the framing members and connecting said foot portions, and yoke anchorage means connecting said end sill and crosstie member and 40 engaging said guide means.

2. In a draft and buffing mechanism for 45 cars having framing members, a yoke member having depending foot portions embracing said framing members, yoke guides extending under the framing members and connecting said foot portions, and anchorage means connecting said framing members and engaging said guides.

3. The combination with an end sill and adjacent crosstie member of a car under-frame, of a draft and buffing mechanism 55 comprising a yoke member having guide means extending under said framing members, and yoke anchorage means connecting said crosstie and end sill and engaging said 60 guide means.

4. In a draft and buffing mechanism for cars having framing members, a yoke member having guide means extending under said framing members, depending foot portions on the yoke embracing the framing 65 members and secured to said guide means, and yoke anchorage means connecting said framing members and adapted for engagement with said guide means.

5. The combination with an end sill and adjacent crosstie member of a car under-framing, of a draft and buffing member having depending foot portions embracing said framing members, a resilient member carried by said framing members, and alining 75 means engaging said foot portions and resilient member.

6. The combination with an end sill and adjacent crosstie member of a car under-framing, of a yoke member having depending foot portions embracing said framing members, a resilient member carried by said framing members, and alining means connecting said foot portions and associated 80 with said resilient means.

In witness whereof I have hereunto set my hand.

VICTOR WILLOUGHBY.
